MAIL BOX SUPPORT

Filed March 14, 1929

FIG. 1.

Inventor

M.L. Trimmer.

Watson E. Coleman
Attorney

UNITED STATES PATENT OFFICE

MOSES LEROY TRIMMER, OF CRAIG, MISSOURI

MAIL-BOX SUPPORT

Application filed March 14, 1929. Serial No. 347,071.

This invention relates to the class of supports and pertains particularly to an improved type of support for receptacles, such for example as mail boxes and the like.

5 The primary object of the present invention is to provide an improved mail box supporting post having means associated therewith whereby it will be prevented from tilting in the earth in which it is set.

10 Another object of the invention is to provide a mail box support wherein is employed an upright member and a horizontal member, the horizontal member being designed for the support of a mail box and having pivotal connection with the upright member, by means of which it can be swung to one side or the other thereof, as necessary, centering means being employed for normally holding the members in a particular relation.

15 A still further object of the invention is to provide a mail box support which may be readily adjusted vertically to raise or lower the box, and wherein horizontal adjustment 25 of a portion of the structure supporting the box may be made with relation to a ground engaging supporting member.

The invention will be best understood from a consideration of the following detailed 30 description taken in connection with the accompanying drawing forming a part of this specification, with the understanding, however, that the invention is not confined to any strict conformity with the showing of 35 the drawing but may be changed or modified so long as such changes or modifications mark no material departure from the salient features of the invention as expressed in the 40 appended claims.

In the drawing:

Figure 1 is a side elevational view of the mail box supporting structure embodying the present invention;

45 Figure 2 is a plan view of the bearing members connecting the supporting post and horizontal bar;

Figure 3 is a sectional view taken upon the line 3—3 of Figure 1;

50 Figure 4 is a detailed view of the lower

portion of the supporting post showing the anchor members in side elevation.

Referring to the drawing in detail where-in like numerals of reference indicate corresponding parts throughout the several views, the numeral 1 indicates a post member designed to be mounted in vertical position in the earth, the lower end of the post having secured thereto at opposite points, the anchor plates or shields 2 and 3, arranged in different vertical planes, in the manner shown:

As is also clearly shown, each of these plates is slightly curved transversely, the concave face of each being positioned against the supporting post. In this manner, when the post is in position and the plates 2 and 3 are below the surface of the ground, the swaying or tilting of the post will be prevented.

Adjacent its upper end, the post 1 has adjustably secured thereto a pair of bearing blocks 4 and 5, the block 4 having a single passage therethrough, as indicated at 6, through which the post 1 passes and carrying a set screw 7 which bears against the post to prevent the movement of this block thereon. Formed transversely of the upper and lower faces of the block 4 are the ribs 8, the upper one of which is designed to position in a recess 9 formed transversely of the adjacent and under face of the upper block 5, in the manner shown, to hold these blocks in a predetermined relation.

The upper block 5 of the bearing members is also provided with a passage for the extension therethrough of the post 1, this passage being indicated by the numeral 10, and as shown, this passage passes through the groove 9, the same as the passage 6 in the lower block passes through the ribs 8.

One side of the upper block 5 projects slightly beyond the lower block and has formed therethrough a second passage, as indicated at 11. This passage extends at right angles to the passage 10 and is designed to receive one end of a horizontal bar 12, which bar is adjustably held therein by a set screw 13.

The outer end of the horizontal bar 12 is provided with suitable supporting brackets 14

and 15 for the support of the letter box 16 and package box 17, in the manner shown.

When the present mail box supporting structure is set up for use, the post 1 may be positioned in the usual manner adjacent a roadway with the box supporting arm 12 extending outwardly therefrom at right angles to the road, so that the boxes 16 and 17 may be easily reached from a vehicle in the road. The tongue and groove connection between the bearing blocks 4 and 5 serves to normally maintain the arm and post in the position described, but will permit of the arm 12 being rotated about the post as the outer end of the bar is struck. It will be readily seen that when the bar 12 is rotated the block 5 will ride up upon the rib 8 of the underlying block and swing about the post 1.

From the foregoing description it will also be readily apparent that the block 4 may be easily raised or lowered upon the post 1 and the bar 12 may be shifted through the block 5, as desired, to increase or decrease the distance between the post and the boxes carried upon the outer end of the bar.

It will be seen also that with a construction of the character described, a number of units similar to the unit 10 may be placed upon the post 1, one above the other, to support a plurality of box carrying arms so that one post may be employed for carrying a number of mail boxes.

Having described my invention, what I claim is:

1. In a support of the character described, a vertically mounted post, a pair of block bodies disposed in superposed relation and having aligned bores for the passage of said post therethrough, one of said bodies having the face abutting the other body provided with a transverse rib, the other body having the face opposing said rib provided with a transverse groove for the reception of the rib, said passages of the bodies passing through the rib and the groove, the upper one of said bodies having a second passage formed therethrough in a plane at right angles to the first mentioned passage, an article supporting arm slidably extended through the second passage of said upper body, and means for detachably securing the lower one of the bodies to the post.

2. In a support of the character described, a vertically mounted post, a pair of block bodies disposed in superposed relation and having aligned bores for the passage of said post therethrough, one of said bodies having the face abutting the other body provided with a transverse rib, the other body having the face opposing said rib provided with a transverse groove for the reception of the rib, said passages of the bodies passing through the rib and the groove, the upper one of said bodies having a second passage formed therethrough in a plane at right angles to the first

mentioned passage, an article supporting arm slidably extended through the second passage of said upper body, a pair of set screws one in each of said bodies, designed to engage the post passing therethrough to secure the bodies and the post in fixed relation, and a second set screw mounted in the upper one of said bodies and adapted to engage said arm to maintain the same in adjusted position relative to the attached body.

In testimony whereof I hereunto affix my signature.

MOSES L. TRIMMER.
